UNITED STATES PATENT OFFICE

MICHAEL SYNOVETZ, OF CLIFTON, NEW JERSEY

MAN'S SOCK

Application filed June 16, 1927. Serial No. 199,168.

This invention relates to a new and useful article in the nature of socks, particularly adapted to be worn by men for the purpose of providing a comparatively short sock.

5 The object of the invention is to provide a short sock embodying comfort and self-fitting qualities.

Fig. 1 illustrates my improved sock as same would appear when in use on the foot of the 10 wearer.

Fig. 2 is a similar view with a portion thereof broken away.

Fig. 3 is a vertical central sectional view of the sock.

15 Fig. 4 is a similar view, but showing the reinforcement thereof in a vertical position.

Fig. 5 is a fragmentary vertical sectional view taken directly within the cuff member, as indicated by line 5—5 of Fig. 6, and

20 Fig. 6 is a transverse vertical sectional view taken on the line 6—6 of Fig. 5.

As here embodied my improved sock consists of the usual toe element 10, heel element 11 and body member 12, made of any suitable 25 material, such as generally used for men's socks. It should be understood that the toe and heel elements 10 and 11 may be reinforced, or may be constructed similarly or identically with the body member 12. The 30 ankle element 13 is comparatively short so as to extend slightly above the ankle of a wearer, and has a top turned down portion 15 for snugly holding the ankle element 13 against the wearer's ankle.

35 A band 18 of flexible elastic material is stitched or sewn, as at 19, to the ankle element 13, adjacent to the upper portion thereof. The above described construction is such as will provide a close fitting sock, and which 40 will definitely determine the line of fold of the upper portion 15.

I have shown a second band 23 stitched as at 24 to the edge of the upper portion 15 of the ankle element 13, in combination with the 45 above mentioned band 18, for the purpose as below set forth.

I have shown a third band 25, stitched, as at 26, to the ankle element 13, intermediate the above mentioned bands 18 and 23, for the 50 purpose as below set forth.

I have also shown a reinforcing member 27 preferably of fibre, bone or thin metal pivotally attached intermediately of its ends, as at 28 to the outer side of the band 25. The free extremities of the member 27 are adapted to engage in a pocket 18' arranged on the outside of band 18 and in a pocket 24' arranged on the inside of band 23 when the member 27 is in a vertical position for holding the bands 18 and 23 in spaced relation. 55 The member 27 may be turned to a horizontal position so that its free extremities will engage in pockets 25' and 26' arranged on the outer side of the band 25 for permitting portion 15 to wrinkle. 60

Having thus described my invention, what I claim as new and desire to protect by Letters Patent of the United States is as follows:

In a sock of the class described, an ankle 70 element having a top turned down portion, a band secured to the ankle element adjacent the fold of the turned down portion, a second band secured to the ankle element beneath the first band, a third band secured to 75 the said turned down portion and positioned below the second band, a reinforcing member pivotally attached intermediate of its ends to the said second band, pockets arranged on the first and third bands for engagement by the free extremity of the reinforcing member 80 when in vertical position, and other pockets arranged on the second band for engagement by the free extremities of the reinforcing member when in horizontal position. 85

In testimony whereof I have affixed my signature.

MICHAEL SYNOVETZ.
